(57) **CLAIM**

The ornamental design for a cleaning device component, as shown and described.

DESCRIPTION

FIG. 1 is a top perspective view of a cleaning device component showing my new design, with a close-up view of a first end of the cleaning device component, for which an opposing second end thereof being a mirror image of the first end and for which the teeth members shown extend uniformly along the entire length of the cleaning device component;

FIG. 2 is a bottom perspective view of the cleaning device component of FIG. 1, with a close-up view of the first end of the cleaning device component, for which the opposing second end thereof being a mirror image of the first end and for which the teeth members shown extend uniformly along the entire length of the cleaning device component;

FIG. 3 is a top plan view of the cleaning device component of FIG. 1;

FIG. 4 is a bottom plan view of the cleaning device component of FIG. 1;

FIG. 5 is a front view of the cleaning device component of FIG. 1, with the rear view being a mirror image of the front view; and

FIG. 6 is a rear view of the cleaning device component of FIG. 1; and,

FIG. 7 is an enlarged left side view of the cleaning device component of FIG. 1, with the right side view being a mirror image of the left side view.

(Continued)

The claimed design is limited to the bottom end portion of the cleaning device component.

The dotted lines shown in the figures are for the purpose of illustrating portions of the cleaning device component that form no part of the claimed design.

The dashed lines shown in the enlarged details define the bounds of the claimed design and form no part thereof.
